UNITED STATES PATENT OFFICE.

ORVILLE V. DUTRO AND ARTHUR S. BURROUGHS, OF SPOKANE, WASHINGTON.

PUNCHING-MACHINE.

1,348,788.

Specification of Letters Patent.

Patented Aug. 3, 1920.

Application filed April 21, 1919. Serial No. 291,675.

To all whom it may concern:

Be it known that we, ORVILLE V. DUTRO and ARTHUR S. BURROUGHS, citizens of the United States, residing at Spokane, in the county of Spokane and State of Washington, have invented certain new and useful Improvements in Punching-Machines, of which the following is a specification.

The present invention relates to improvements in punching machines, especially adapted for use in connection with web printing presses, for puncturing the printed web so that it may subsequently be severed into sheets with the printed matter thereon. The invention involves an attachment operated from the power applied to the printing press and as a part of the printing machine, for accurately and automatically puncturing or perforating the web in relation to the printing, and for this purpose involves a plurality of punches located transversely of the machine, and adjustable both transversely and longitudinally of the machine for adapting the printing press to different lengths of sheets as required.

Figure 1 is a side elevation of a portion of a web-feed printing press, showing so much thereof as is necessary to illustrate the application thereto of the present invention.

Fig. 2 is an enlarged view, partly in section, showing one end of the carrier frame and one of the web or paper punches, the other end of the carrier frame being substantially similar to that shown herein in section.

Fig. 3 is an enlarged, transverse sectional view of the carrier frame showing also one of the punches.

Fig. 4 is an enlarged view of one of the dies, broken away, and Fig. 5 is a top plan view of the same die.

In actual use, a plurality of the punches, indicated as a whole by the letter P, are used, and these punches are located over the top of the printing press feeder in the path of travel of the web W, and supported for lateral adjustment on the four frame bars 1, 2, 3, 4, which in turn are supported, at their ends by housings as H, only one housing being here shown, and both housings being longitudinally adjustable of the printing press frame F upon which they are slidably supported. Thus it will readily be understood that the punches may

be adjusted transversely of the printing press to puncture the web at various points across the web, and the carriage frame including the bars and housings may be adjusted longitudinally of the printed web to puncture or punch the web into different lengths of sheets as required.

The four supporting or frame bars 1, 2, 3, 4 are secured as by nuts 5 on their threaded ends in the housings, while the bar 4, which is a hollow bar, has passed therethrough an operating shaft 6, the hollow bar being secured in the housing at its ends by a nut as 7, and the shaft, which projects at both ends beyond the ends of the hollow bar, having a gear or rack wheel 8 fixed near each end, and at one end is provided with a handle wheel 9. The gear or rack wheels 8 engage a fixed rack or rack bar 10, on a plate 11 at each side of the printing press feeder, and as the plate is stationary and fixed on the frame F of the appliance, it will readily be apparent that by turning the hand wheel 9 the carriage frame may be moved longitudinally of the feeder frame, the carriage housings sliding over the plates 11 and the rack wheels engaging the rack bars.

Each punching device includes a punch or plunger 12 and its die block 13, the former being vertically reciprocable in the bushing 14 which has a knurled head 15 and at its other end is provided with screw threads to receive the stationary nut 16. Between the head and the nut a clamp block 17 is held, the bushing passing through both the block and the nut, and the block is grooved on its underside as at 18 to engage the upper surfaces of the two bars 1 and 3, the nut 16 being fashioned to engage these same bars at their under sides. In this manner the bushing is rigidly clamped between the two, bars 1 and 3 and functions as a rigid and efficient guide for the reciprocable plunger or punch.

The die block 12 is located directly beneath the punch, and the block is fashioned as the head of a threaded bushing 19, which, at its lower end is equipped with a lock nut 20 that bears against the under side of a clamp block 21 that is perforated at its center to fit over the bushing. This clamp block is also grooved, as at 22, to engage the under sides of the two bars 2 and 4, and in Fig. 3 it will be clearly seen that when the nut 20

is turned, the die block or head 12 is brought down into close frictional contact with the upper face of the two bars and the clamp block is caused to engage the lower faces of these bars, thus rigidly clamping the bushing to the bars, beneath the punch. In the upper end of the die head, an annular recess 23 is provided, the recess being arranged eccentrically to the bore of the bushing, and within the recess a die plate 24 is placed to receive the punch. Thus by turning this eccentric bushing, the punch and die plate may be quickly and with facility brought into accurate alinement. The web passes between the punch and the die plate, the former being above the web and the latter below the web and the two members of the punching device may be slid along on the supporting bars 1, 2, 3, 4, to desired position, and then made to coincide by first positioning the parts in order that the punch will pass through the die plate, and then the two members of the device may be locked in position, one by turning the knurled head of the punch bushing and the other by turning the nut on the die bushing.

The punch is vertically reciprocated to puncture the web and pass into the die ring, and out again, the motion being imparted thereto from the power applied to operating the printing press, and the actuating device for the punch includes a rock shaft 25 extending longitudinally of the printing press and supported in journal bearings at its outer side, which is operated or oscillated through the connection 26 from suitable mechanism, the oscillation of the shaft of course being at predetermined intervals. The actuating shaft is preferably square or rectangular in cross section, and has thereon the crank arm 27 which may slide on the shaft when the carriage frame is to be adjusted longitudinally of the printing press. The crank arm has a vertical pivoted link 28 extending up alongside the housing and the upper end of this link has pivoted thereto a rock arm 29 fixed on the transverse, counter shaft 30 which also is adapted to rock or oscillate synchronously with the oscillating or actuating shaft 25. This latter shaft thus reciprocates the punches through the instrumentality of the counter-shaft which has a direct connection to each punch through a forked lever arm 31 that is fixed to the counter-shaft by a set screw 32 and en-

gages a pin 33 that passes transversely through the upper end of the punch stem.

A bracket arm 34, rigid with the housing extends downwardly therefrom into the forked crank arm on the square actuating shaft so that the crank arm is moved along on its oscillating shaft with the movement of the carriage frame, and the carriage frame may be locked in fixed position on the rack plate 11 by means of the lock screw 35 passing vertically through the housing.

What we claim is:—

1. The combination in a punching machine with the two pairs of transverse bars forming a carriage frame, of a punching device supported on the carriage frame and comprising a die member and a punch member in reciprocal relation thereto, means for reciprocating the punch member, one of said bars being tubular, and actuating means including a coöperating member in the tubular bar for moving the carriage frame. 70 75

2. The combination with a longitudinally adjustable carriage frame including the four transverse bars one of which is hollow, of the punching devices adjustably held on said bars, a supporting frame and a rack bar thereon, a rack shaft passed through said hollow bar and a rack wheel on said shaft engaging the rack bar, for moving the carriage frame. 80 85

3. The combination with the carriage frame including the transverse supporting bars arranged in horizontal pairs, of a punch member and means for clamping it on the upper pair of bars, a die member and means for clamping it on the lower pair of bars in operative relation to the punch member, and means for operating the punch member. 90

4. The combination with the two pairs of supporting bars, of a punch bushing, a punch clamp block and a clamp nut for rigidly securing the bushing and block to the upper pair of bars and a reciprocal punch in said bushing, a second bushing beneath the punch bushing having a die head, a clamp block, and a lock nut for securing the bushing in operative position to the lower pair of bars, and means for operating the reciprocal punch. 95 100 105

In testimony whereof we hereunto affix our signatures.

ORVILLE V. DUTRO.
ARTHUR S. BURROUGHS.
